UNITED STATES PATENT OFFICE

2,602,885

RADIO SIGNALING

Edwin H. Armstrong, New York, N. Y.

Application March 30, 1946, Serial No. 658,403

1 Claim. (Cl. 250—6)

1

This invention relates to improvements in radio signaling, particularly to the broadcast art and more specifically to the F. M. or frequency modulation broadcast art.

It has for its object the provision of means to enable the listener to a broadcast program to preset the relative levels of the loud speaker output at which the musical parts of the program as distinguished from advertising talks are reproduced and maintaining meanwhile the desired difference in level automatically in accordance with the character of material transmitted from the broadcast station.

This invention is particularly useful in F. M. broadcasting because it has been noted that it is possible to run the levels of the musical part of the programs higher than would be possible with an ordinary amplitude modulation or standard broadcast transmission without distress to the ear because of the much lower percentage of distortions in the F. M. system.

This invention is an improvement on my U. S. Patent No. 1,941,067 which describes a method of accomplishing the basic purpose of the idea expressed here, wherein, whenever an advertising talk is broadcast, there is transmitted simultaneously an inaudible tone from the transmitter which, when received by the listener's set actuates a relay which cuts out the driving coil of the loud speaker, thereby silencing its output. The purpose described herein could be accomplished by connecting across the relay contacts a variable resistance which could be adjusted to values of different impedances in circuit with the coil but it is desirable to employ electronic means to do this rather than these more or less mechanical means.

Referring now to the figures which form a part of this specification Figure 1 illustrates one form of the invention which shows the general theory of the system;

Figure 2 illustrates a form of this invention in which a minimum number of tubes are employed to carry out the idea, a matter of considerable importance in the manufacture of broadcast receivers;

Figure 3 shows a modification of a portion of Fig. 2 for the purpose of securing additional control of the silencing effect, as hereinafter explained.

Figure 4 illustrates the general arrangement of the transmitting system, and corresponds to Figure 1 of Patent #1,941,067 hereinabove referred to.

Similar characters of reference designate similar parts in each of the several views.

2

Referring now specifically to Figure 1, 1—7 represents the ordinary F. M. receiver, 8 the restorer, 9 the first audio amplifier stage, 10 the final audio stage, 11 the loud speaker, 12 a high pass filter for blocking out the low frequency program currents, but which passes the super-audible frequency transmitted simultaneously with the advertising talks, 13 an amplifier for this frequency, 14 a sharp circuit, or series of sharp circuits for selecting it from all other frequencies, 15 a rectifier arranged with a threshold so that small static disturbances or any residual components of the program will not be rectified, 16 a D. C. filter having a substantial time constant so that impulses of short duration cannot produce variations in the amplification of the audio system at a rate which will be audibly perceptible, and 17 a voltage divider for adjusting the amount of control voltage to be applied to the control of amplification of the amplifier 9.

The basic principle of operation is along the lines laid down in the patent previously referred to. In accordance with the teachings of that patent an inaudible frequency is transmitted with a low degree of modulation along with the main program material whenever it is desired to give the listener a choice of selectively cutting out, if he so desires, the program material. In this present arrangement which is embodied in a wide band frequency modulation system, an auxiliary modulating signal of the order of 20,000 cycles having a swing of five to fifteen or twenty kc. may be effectively employed.

This frequency is received in the ordinary manner, demodulated by the discriminator 6 and the detector 7, selected out from the program material of lower frequency by the high pass filter 12, amplified by the tube 13 and passed thru a sharply tuned filter to separate it from program harmonic contents, shock excitation currents such as those produced by automobile ignition, etc. The output voltage of the filter is applied to a biased back rectifier or rectifier with a threshold or minimum operational voltage which is obtained in a manner which will be described hereinafter. The twenty kc. current, after rising to a level sufficient to overcome the threshold, is rectified, and converted into a direct current. This current is passed thru a low pass filter having a sufficiently long time constant so that the rate of change of current passing thru it varies at a sub-audible rate. This insures the system from having noise produced in the audio amplifiers by disturbances which have succeeded in passing the various selective means previously mentioned that guard against them. The output of the filter is

terminated in a voltage divider which enables any percentage of the quieting voltage developed by the auxiliary frequency to be impressed on the control elements of the vacuum tube amplifier 9, so that any relative balance between program material transmitted with and without the auxiliary frequency may be obtained.

The various controls above referred to must be applied to the actuation of the degree of amplification without introducing distortion in the reproduction when the auxiliary control is in use and without introducing noise into the speaker system when it is applied.

Referring now specifically to Figure 2, there is illustrated therein an arrangement for carrying out the purpose of the invention in a simple manner. One tube only is required and the result is achieved without the introduction of distortion or noise in the speaker system.

In this figure 20 represents the discriminator or selective system-detector output and 21, 22 the usual restorer for compensating for a pre-emphasized transmitted signal. 23 is the usual audio amplification control and 24 the first stage of the audio amplifier. This amplifier is of the pentode type for reasons which will appear hereinafter and its bias is obtained by a combination of a cathode dropping resistor 25 and a resistance 26 connected between cathode and the source of plate potential. The grid leak consists of the resistors 28, 30, the last of which may be cut out by means of the switch 45.

The output of the amplifier 24 is developed across the plate load 28 and passed on to the succeeding stage in the usual manner. With the exceptions noted the parts of the system just described represent the usual detector output and first amplifier of an ordinary standard F. M. receiver.

The additional features are embodied in the system 31-45. Referring now to this part of the figure 31, 32, 33, 34 represents a high pass filter connected between the detector output and the amplifier 35. 36 is a bias resistor which, as will be hereinafter explained in more detail, furnished the bias voltage for the pentode amplifier 35 and the threshold bias for the diode 40. 38, 39 represents a tuned coupled circuit adjusted to select the auxiliary frequency and exclude all undesired frequencies; 41, 42 and 43 represent a low pass filter designed to separate out the rectified D. C. current output of the diode 40 from all variable current components so that no variation of potential at an audible rate can occur across the output potentiometer 44, which controls the amount of voltage applied to the suppressor 46 of the amplifier 24. 45 is a switch for applying the control voltage developed across the filter output to the control grid of the amplifier 24 simultaneously with its application to the suppressor 46 of that amplifier.

The operation of the system will be understood from the following description. When the auxiliary frequency is applied at the transmitting end of the system a frequency deviation at some inaudible rate and of the order of five or ten per cent of the maximum program deviation is imparted to the wave. This develops, under ordinary circumstance an E. M. F. of the order of 1 volt across the detector output which is selected out by the high pass filter 31-34 and amplified by the tube 35. The amplified voltage of inaudible frequency is impressed across the diode 40 and is of sufficiently high level to overcome the threshold imposed by the negative bias

across the resistance 36. The direct current component is selected out by the filter 41, 42, 43 which has a sufficiently long time constant to permit the voltage across the potentiometer 44 to build up at an inaudible rate. This voltage or any desired fraction of it is impressed in the negative polarity on the suppressor grid 46 of the amplifier 24 so as to reduce its amplification factor whenever the auxiliary frequency is transmitted by an amount depending on the setting of the potentiometer 44. This can be accomplished without the introduction of distortion over a substantial volume range without difficulty. Where, however, it is desired to completely cut off the speaker system when the auxiliary frequency is on, a larger negative voltage than is readily available for use on the suppressor may be required. In this event the negative voltage supplied to the suppressor may also be impressed on the control grid of the tube 24 by means of the switch 45. This switch may be arranged to be controlled synchronously with the potentiometer adjustment 44 so as to be cut in when the point of maximum negative voltage application to the suppressor is reached. Under these conditions the amplification of the tube 24 is reduced to zero.

It will be understood that the tetrode 35 and the diode 40 can be enclosed in a single envelope so that a single tube is all that is needed to carry out the invention in all its aspects.

It should be noted that the negative bias for the amplifier 24 is obtained by a combination of cathode dropping resistor and plate bleeder resistance 26. The effect of this arrangement is to keep a constant bias on the control grid of the amplifier regardless of the change in the current through the tube when a negative voltage is supplied to the suppressor grid.

Referring now to Fig. 3, which shows the control means for effecting the alteration in level between the different parts of the program, an alternative method of obtaining the threshold voltage for the diode 40 is illustrated. In Fig. 2 the threshold is, as has been already described, obtained by utilizing the grid bias voltage of the amplifier 35. Under some circumstances this threshold may not be sufficiently high. A method of obtaining a threshold which may be adjusted to any desirable level is shown in Fig. 3 by utilization of a potentiometer 50, arranged to supply positive voltage to the cathode of the tube 40 by connecting it in the manner shown, between the anode source of supply voltage and ground. A by-pass condenser 51 supplies a path of low impedance for the superaudible frequency current, in accordance with standard practice. The closer the midpoint of the potentiometer is moved to the source of anode potential, the higher the threshold. This threshold potential has the effect of rendering the rectifier less sensitive to noise currents and enabling more effective separation of the inaudible control current from the noise current, when signal intensities become low.

It is possible to utilize the amplification control mechanism 31-44, as shown in Figs. 2 and 3, to effect noise silencing when the receiver is tuned from one broadcast station to another by so designing the relative amplification of the amplifier 35 and the band width of the selective circuits 38-39 that a proper proportion is obtained between the noise and control frequency voltages which are applied to the diode 40 with its respective threshold. The variable potentiometer

50 provides a simple practical means of selecting the proper threshold voltage for various noise conditions.

Referring now to Figure 4 which illustrates simply the transmitting end of the system 61—62 represents the announcement microphone and its associated amplifying system, and 63—64 represents the studio microphone and amplifier for picking up the musical part of the program. 65—66 is a switch for throwing over from one microphone to the other, and 67 is a simultaneously operated switch for throwing on to the modulating input 71 which may extend, for example, to an F. M. radio transmitter (not shown) a superaudible modulating frequency from the source 68—69—70. A frequency of the order of 20,000 cycles may be used. This frequency is chosen so that it will be inaudible and will not, therefore, affect the reception on ordinary receivers.

I have described what I believe to be the best embodiments of my invention. I do not wish, however, to be confined to the embodiments shown, but what I desire to cover by Letters Patent is set forth in the appended claim.

A radio receiver adapted to receive and reproduce currents of program frequencies and control signal currents of an inaudible frequency accompanying parts of the program, comprising means for receiving and reproducing such program frequencies together with such inaudible frequency when present, frequency selective means for selecting said inaudible frequency from the program frequencies, rectifying means responsive to currents of the resulting selected inaudible frequency having more than a predetermined level and unresponsive to currents below said level for producing a direct current control voltage, direct current filter means for filtering out variations in the resulting direct current control voltage, an amplifier for the repro-

duced program frequencies, said amplifier having a suppressor grid, manually operable adjusting means for adjustably selecting any desired value of said direct current control voltage between an upper and a lower limit thereof, and circuit means for applying the selected control voltage to the suppressor grid of said amplifier to control the level of amplification thereof, said amplifier having a control grid with means for applying a constant bias thereto, said bias means including a cathode dropping resistor and means for applying a voltage drop to said cathode resistor regardless of the change in current through the amplifier when a negative voltage is supplied to the suppressor grid.
